UNITED STATES PATENT OFFICE.

ROBERT BOBINS, OF CHICAGO, ILLINOIS.

BUCKLE.

1,362,668.

Specification of Letters Patent. Patented Dec. 21, 1920.

Application filed April 21, 1919. Serial No. 291,700.

To all whom it may concern:

Be it known that I, ROBERT BOBINS, a citizen of the United States, residing at Chicago, in the county of Cook and State of Illinois, have invented new and useful Improvements in Buckles, of which the following is a full, clear, concise, and exact description, reference being had to the accompanying drawing, forming a part of this specification.

10 This invention relates to buckles and more particularly to belt buckles.

The invention has among its objects to provide a self-locking buckle which will permit the insertion of the free end of the belt 15 but will automatically lock the belt against withdrawal after it has been adjusted to the desired length.

A further object is to provide a construction which will adapt itself to different 20 thicknesses of belts.

Another object is to provide a buckle having means for easily and quickly clamping one end of the belt thereto, and also clamping means which may be readily released 25 when desired.

A still further object is to provide a construction of buckle which will have means for detachably securing one end of a strap or belt thereto, and also means for automatically locking another portion of the belt thereto.

A still further object is to provide a construction which will automatically grip a belt against withdrawal when the belt is inserted therein, and a construction which does not mar or pierce the belt.

I have illustrated one embodiment of my invention in the accompanying drawings and in these drawings,—

40 Figure 1 is a longitudinal sectional view of a belt having my improved buckle in place thereon;

Fig. 2 is a longitudinal sectional view similar to Fig. 1 but having the buckle in 45 the strap-releasing position;

Fig. 3 is a bottom plan view of the construction shown in Fig. 1, a portion of the buckle being shown in open or strap-releasing position; and

50 Fig. 4 is a transverse sectional view taken on line 4—4 of Fig. 1.

The body portion 10 of the belt buckle is substantially U-shaped in section, as shown in Fig. 4, and is preferably formed of metal, 55 the outer surface of which may be engraved or otherwise suitably ornamented. This

body portion is provided with flanges 11 to which the buckle is connected by means of a pivot pin 12. The buckle is made up of a releasing member 13, pivotally mounted on the pin 12 and also substantially U-shaped in section, the member 13 having secured thereto means for clamping the opposite ends of a belt. The means for adjustably securing the free end of the belt will first be described, and this means comprises a cam member 14 having a pair of arms 14^a formed integral therewith pivoted on the pivot pin 12 above referred to, and normally spring pressed in a direction toward the strap engaging surface 15 of the portion 10 by means of a coiled spring 16. This spring is carried by the pivot pin 12 and is provided with outwardly extending ends 17 and 18, the end 17 engaging a portion 19 of the releasing member 13 of the buckle, and the end 18 engaging one of a pair of dogs 20 formed integral with or suitably secured to the arms 14^a of the cam member 14, as clearly illustrated in Fig. 3. The releasing member 13 of the buckle is cut away or recessed as shown at 21, to permit the rotation of the cam member 14 about its pivot. The dogs 20 are extended as shown in Fig. 3 to a position overlapping a portion 22 of the releasing member 13, this portion 22 limiting the movement of the cam member 14 about its pivot in one direction.

As above stated, the releasing member 13 of the buckle is rotatably mounted on the pivot pin 12 and as this member is rotated in a direction away from the member 10 to the position shown in Fig. 2, the cam member 14 will also be rotated and will be disengaged from the free portion of the belt, since the dogs 20 above referred to will be engaged by the portion 22 of the releasing member 13.

In addition to the belt engaging member 14 I have also provided upon the releasing member 13 means for detachably clamping the opposite end of the belt thereto, this means comprising a clamping member 23. The member 23 is pivoted to the opposite end of the releasing member 13 from the pivot pin 12 and is substantially U-shaped in longitudinal section, the end of the member 23 at one side of the pivot being provided with a series of teeth 24 for clamping an end portion 25 of the belt against the body member 13 of the buckle, and the opposite end of the member 23 is curved as shown at 26, the curved portion fitting over the opposite end

of the member 14 and the intermediate part 5 of the clamping member forming a cover plate for protecting the dogs 20 and spring 16 from contact with the clothes of the wearer of the belt. The portion 22 of the releasing member 13 is also provided with a flange 27 which forms a stop for the end 25 of the belt and prevents the end from being inserted too far in the buckle. In order to 10 clamp the end 25 of the belt it is merely necessary to swing the clamping member 23 from the position in dotted lines in Fig. 1 to the position shown in full lines. The central portion of the clamping member is slotted 15 as shown at 28 in Fig. 3, these slots being provided to permit the rotation of the cam member 14 through a greater angle of movement, thereby adapting the buckle to belts of greater thickness than would be possible 20 were the movement of the dogs 20 limited by the cover portion of the clamping member 23.

The operation of the construction above described is simple, but will be briefly set forth. One end of the belt is first inserted 25 in the buckle to a position where the extreme end engages the flange 27, the clamping member 23 being swung to the position shown in dotted lines in Fig. 1. When this end has been so inserted, the clamping member is swung to the full line position, thereby firmly securing the end 25 of the belt against removal. After this has been done the opposite end 29 of the belt is inserted 30 beneath the surface 15 of the body portion 10 of the buckle, and as this portion of the belt contacts with the cam 14, the cam will be swung in a counter-clockwise direction about its pivot, thereby permitting the 35 free entrance of the belt. When the portion 29 has been adjusted to the desired position, it is released and the cam member 14 securely clamps the belt against withdrawal. When it is desired to loosen the belt the 40 wearer rotates the releasing member 13 of the belt and the parts attached thereto, about the pivot 12, to a sufficient distance to withdraw the cam from engagement with the surface of the end portion 29 of the 45 belt. In practice merely a slight rotation is needed and the end portion 29 may then be withdrawn.

While I have in the above specification shown and described but one embodiment of 50 my invention, it should be understood that the invention is capable of modification, and that changes and modifications may be made without departing from the spirit and scope of the invention as expressed in the following claims.

Having thus described my invention, what I claim as new and desire to secure by Letters Patent, is—

1. In a buckle, a body member, a releasing member pivoted thereto, a cam disposed

at one end of said releasing member for gripping a belt, and means disposed at the opposite end of said member for gripping another portion of the belt, said last named means having a portion adapted to shield 70 said cam.

2. In a buckle, a body member, a pivot pin carried thereby, a spring pressed belt engaging member carried by said pivot pin, a second member carried by said pivot pin 75 and having a portion disposed in the path of said belt engaging member, and supplemental means carried by said second member for engaging another portion of said belt. 80

3. In a buckle, a body member, a member pivoted thereto, gripping means for engaging and gripping a portion of a belt, said resilient means having outwardly extending dogs, means carried by said pivoted member 85 for engaging and gripping another portion of the belt, said last named means being slotted to permit movement of the dogs therethrough.

4. In a buckle, a pivoted member, a cam 90 member having dogs, means for forcing said cam member in engagement with a portion of the strap, a cover plate for shielding said cam member and dogs, said cover plate being slotted to permit the movement of said 95 dogs therethrough.

5. In a buckle, a body member, a pivot pin carried thereby, a releasing member carried by said pivot pin, a cam carried at one end of said releasing member for gripping a 100 belt, and means disposed at the opposite end of said releasing member for gripping another portion of said belt, said last named means housing said pivot pin and cam.

6. In a buckle, a body member, a pivot 105 pin carried thereby, a cam on said pivot pin for gripping a belt, a spring surrounding said pivot pin to normally hold said cam in gripping engagement, and means disposed on said releasing member for gripping the opposite end of said belt, said last named means housing said pivot pin, spring and cam. 110

7. In a buckle, a body member, a releasing member having gripping members for 115 gripping the ends of a belt, one of said gripping members serving as a housing for the other gripping member.

8. A belt buckle comprising a main body portion having a face-plate portion, and a 120 pair of side flanges between which one end of the belt is received, a pivot pin extending across from one flange to the other, a gripping member pivotally mounted on said pivot pin between which and said body portion one end of the belt is gripped, and a releasing member also pivotally mounted on said pivot pin for releasing said gripping member. 125

9. A belt buckle comprising a main body- 130

portion having a face-plate portion, and a pair of side flanges between which one end of the belt is received, a pivot pin extending across from one flange to the other, a gripping member pivotally mounted on said pivot pin between which and said body-portion one end of the belt is gripped, and a releasing member also pivotally mounted on said pivot pin for releasing said gripping member, and means for securing the other end of the belt to said pivoted releasing member.

10. A belt buckle comprising a main body-portion having a face-plate portion, and a pair of side flanges between which one end of the belt is received, a pivot pin extending across from one flange to the other, a gripping member pivotally mounted on said pivot pin between which and said body-portion one end of the belt is gripped, and a releasing member also pivotally mounted on said pivot pin for releasing said gripping member, and means for securing the other end of the belt to said pivoted releasing member, comprising a dog pivoted on the swinging end of said releasing member.

11. A belt buckle comprising a body-portion having a face-plate portion and a pair of flanges between which one end of the belt is received, a pivot pin extending from

one to the other of said flanges, a gripping member for gripping one end of the belt against the body-portion, said gripping member having a pair of arms having a pivotal engagement with said pivot pin, a releasing member for releasing said gripping member, said releasing member having a pair of flanges between which the other end of the belt is received, said flanges having a pivotal engagement with said pivot pin.

12. A belt buckle comprising a body-portion having a face-plate portion and a pair of flanges between which one end of the belt is received, a pivot pin extending from one to the other of said flanges, a gripping member for gripping one end of the belt against the body-portion, said gripping member having a pair of arms having a pivotal engagement with said pivot pin, a releasing member for releasing said gripping member, said releasing member having a pair of flanges between which the other end of the belt is received, said flanges having a pivotal engagement with said pivot pin, and a gripping jaw for gripping the belt pivotally mounted between the flanges of the releasing member.

In witness whereof I have hereunto subscribed my name.

ROBERT BOBINS.
